(57) **CLAIM**

The ornamental design for an adhesive sheet material application device, as shown and described.

DESCRIPTION

FIG. 1 is a perspective view of the subject device;
FIG. 2 is a top plan view of the subject device;
FIG. 3 is a front elevation view of the subject device;
FIG. 4 is a left side elevation view of the subject device;
FIG. 5 is a back elevation view of the subject device; and,
FIG. 6 is a bottom plan view of the subject device.
The right side elevation view is a mirror image of the left side elevation view.
